BY

UNITED STATES PATENT OFFICE.

ALBERT LARSON, OF WASCO, ILLINOIS.

HAND TWINE KNOTTER AND CUTTER.

No. 895,277.

Specification of Letters Patent.

Patented Aug. 4, 1908.

Application filed September 3, 1907. Serial No. 391,071.

To all whom it may concern:

Be it known that I, ALBERT LARSON, citizen of the United States, residing at Wasco, in the county of Kane and State of Illinois, have invented certain new and useful Improvements in Hand Twine Knotters and Cutters, of which the following is a specification.

My invention relates to implements designed to facilitate the application of the cord used in securing packages.

The chief objects of my invention are to produce a device that will enable the operator to apply a cord to a package with unusual rapidity; to provide means for holding the twine during the process of wrapping; to quickly and effectually knot the twine after it has been applied and to furnish means for automatically severing the string subsequently to the knotting operation.

I accomplish the above mentioned results by the use of the implement illustrated in the accompanying drawing which forms a part of this specification, and in which,

Fig. 1 is a side elevation of my package tying instrument showing method of its application; Fig. 2 is an end elevation, a portion of the operating lever being broken away; Fig. 3 is a transverse section through the bearing with the gears and knotter removed; Fig. 4 is a transverse section through the base plate and gear bearing looking in a direction opposite to Fig. 3; Fig. 5 is a fragmentary view of the cord tensioning device the bearings being shown in section; Fig. 6 is a fragmentary view showing the method of locking the knotter pinion; Fig. 7 is a fragmentary view of the under side of the base plate to illustrate the jaw opening cam; Fig. 8 is a plan view of the jaw closing arm; Fig. 9 is a top plan view of the knotter pinion; Fig. 10 is a cross-section through the long of the operating lever, and Fig. 11 is a fragmentary top plan view of the pawl lever and knife arm.

Referring to the drawing more in detail the numeral 11 indicates a base plate, to which is firmly attached a supporting handle 12, supplied at the free extremity with a finger ring 13. Placed above said handle, and coacting therewith is an operating lever 14, pivoted to a post 15, and supplied with a thumb ring 16. Near the front margin of the said plate 11 is a support or frame 17,

consisting of two posts 18, joined above to support a bearing block 19 for a stud 20 upon which is journaled a mutilated bevel-gear 21, the said stud being secured in position by a set-screw 22. The said gear meshes with a pinion 23 mounted on a spindle 24, the upper end of which is received in a socket 25 in the block 19, its lower end passing through the base plate 11.

The teeth of the main driving gear are omitted at spaced intervals, thus forming blank portions 26, the periphery of the wheel at these points having an increased radius. The number of teeth in each of the segments thus formed corresponds with the whole number of teeth in the pinion, and the latter will thus be given one complete turn for each segment. The margin 27 of the blank portion is received in a notch 28 formed in the collar or hub 29 of the pinion, and thus locks the said pinion against movement so long as said blank is in engagement with the notch. The driving gear is operated by means of said lever 14, which is held in extended position by a spring 30. The lever passes across the rear face of the gear to facilitate its operative engagement successively with pins or lugs 32, which project from the rear face of the gear. The said lever will engage one of the lugs 32 when the lever is moved downward and on its return will yield sufficiently to ride over the succeeding lug, the rear margin of the lever being provided with an inclined face, as shown in Fig. 10.

The lower end of the spindle 24 is furnished with an oval shaped head 34, and through the shaft is passed a clamping jaw 90 which rocks on a pivot 36. The rear portion 37 of said jaw carries a friction roller 38 which bears upon an inclined arm 39 during a part of a revolution of the said shaft, its action being to close the jaw against the beak 40 of the head. The jaw 35 is opened through the engagement of its rear portion 37 by the inclined margin of a sleeve 41 which surrounds the spindle 24 as it leaves the underside of said plate 11. The edge of said sleeve is inclined sharply downward, as shown at 42, to engage the rear end of the jaw and beyond this is an abrupt shoulder 43 which quickly releases the jaw, as the spindle rotates, and affords opportunity for the arm 39 to press the end 37 in the opposite direc-

ion at the proper time to close the said jaw. This mechanism carried by the lower end of the spindle 24, constitutes the knotter. Co-acting with the knotter, and operated by the lever 14 is a tension device which consists of a wheel 44, mounted between posts which depend from the plate 11. The wheel 44 has spaced teeth 45, and is operated by a pawl 46, passing through a slot in the base plate 10 held by a spring 46^a and provided with an arm 47, pivoted at one end in posts 48, the other end of the pawl being projected across the path of the operating lever. A coiled spring 49 holds the arm 47 in its initial position.

A cord severing means is furnished by a knife 50 provided with a spring 50^a and having an extension 51 which crosses the path of the operating lever, but at a lower level than 20 the tension operating arm so that the action of the knife will be delayed to the proper moment, which is subsequent to the operation of the tension wheel.

The manipulation of the device to facilitate the application of a cord to a package is as follows: The operator takes the implement in his left hand, the thumb engaging the ring 16 of the lever 14 and two or more fingers the ring 13 of the handle 12. As an initial movement it is necessary to attach the free end of the cord 51 to the tension device which is done by placing the end of the cord in the notch 52 formed between the front margins of the members and the adjacent tooth, and 35 turning the tension wheel one step by bringing the lever downward towards the plate, through the action of the left hand which is grasping the levers. By this means the tooth which lies in front of the cord will carry a portion between the posts, and the bight thus formed will be clamped between said posts 45 and the tooth, as shown in Fig. 5. The cord will now be held firmly, and the operator seizes the slack portion *a* of the cord 40 which lies beyond the tension wheel, and drawing it towards himself makes a single turn about the beak 40 of the knotter. The cord is then passed as many times as desired about the package 53 and another turn is 45 taken about the beak and the string then carried inward to engage the notch 52 in the tension device. The operator then closes the left hand thus revolving the driving gear 21 to operate the tension wheel which grasps 50 the portion of cord last placed in its notch; to rotate the knotters, to secure the cord, and, lastly, to sever the cord by the action of the knife 50, these movements following each other in proper time and sequence. The action of the knotting mechanism described more in detail is as follows: As the pinion 23 is revolved, the beak of the knotter about which the cord has been given a couple of turns will be carried to the left about the axis

of the spindle, until approximately a half revolution has been made, and the beak is approaching the parallel cords *b* stretched between the said beak and the tension wheel where they are clamped. At this moment, the end 37 of the jaw engages the incline 42 of the sleeve 41 and the said jaw is opened. As it moves on it engages the said portions *b* of the cord and at this point the movable jaw is released by the shoulder 43 and the end of the jaw is engaged and closed firmly upon the 75 cord held therein by means of the arm 39. The lever 14 has now reached the limit of its downward excursion, the knife 50 has severed the cords *b*, and the knotting operation is completed by giving the device a sharp quick 80 jerk to the left which will dislodge the turns of cord about the beak and the loops thus formed will be settled into a firm knot about the ends which are still held in the jaws, having been pulled through the said loops as the 85 instrument is jerked to the left. If this sudden movement is not sufficient to relieve the ends from the jaws a more forcible effort may be made, or the jaws can be opened by operating the lever 14. The end of the cord attached to the source of supply will still be held in the tension clamp and the device will be ready for another operation.

Any form of knotting device may be employed, such, for instance, as that in common 95 use in self binding harvesters:

Having thus described my invention, what I claim as new is

1. In a device for the purpose specified, the combination with a cord knotting device, 100 and an operating lever, of tensioning means coöperating with said knotting device, and means for severing the cord.

2. In a cord manipulating device, the combination with a knotting device, of means for 105 intermittently operating said device, a tensioning means coöperating with said knotting device, and means for automatically severing the cord.

3. In a cord manipulating device the combination with a knotting device, of operative 110 means for aid knotting device, said means consisting of a mutilated gear, an operating lever adapted to intermittently rotate said gear, a tensioning device coacting with said lever, and cord severing means also coacting with said lever.

4. In a device for the purpose stated, the combination with a base plate and a twine knotting device, of a mutilated gear adapted 120 to intermittently operate said knotting device, an operating lever, a twine tensioning device consisting of a toothed wheel, bearings for said wheel adapted to coöperate therewith to clamp the twine, and means for 125 severing the twine.

5. A device for the purpose stated, including a supporting plate, knotting mechanism,

a mutilated gear adapted to intermittently operate said knotting mechanism, an operating lever for said gear, a toothed wheel adapted to clamp a cord, a pawl for said toothed wheel, means coöoperating with said operating lever for actuating said toothed wheel, and a cutter automatically severing the cord.

In testimony whereof I affix my signature in the presence of two witnesses.

ALBERT LARSON.
